UNDERGARMENT

Julius Schwartz, Astoria, N. Y.

Application April 21, 1947, Serial No. 742,765

2 Claims. (Cl. 2—224)

1

This invention relates to an undergarment composed of three pieces constructed and arranged to permit unrestricted leg movements of the wearer without binding or bunching, and to present a substantially straight buttocks line.

Prior undergarments of this type are notched or cut-out on the outer sides of the legs to increase the comfort of the wearer but such results in an undue bunching of material at the crotch in sitting or walking and a pulling and straining of material during sitting. While such undergarment are intended as snug fitting, they are actually unable to fulfill such function as they contain excess material which becomes visibly apparent under thin or close-fitting outgarments, and which becomes uncomfortable in use in many positions or activities of the wearer. In those garments of minimum material cut V-shaped, the rear line is steeply ascending on either side of the crotch which forms an undesirable ridge or shadow under the outgarments, and which is uncomfortable to the wearer in the crotch and buttocks regions. These disadvantages have not heretofore been successfully overcome so far as I am aware.

It is, accordingly, one of the objects of this invention to provide an undergarment which is snug and smooth fitting, with a minimum of material but without being subject to the above and other disadvantages commonly found in garments of this type.

Another object of the invention is to produce an undergarment, the leg portions of which are deeply notched or cut-out in the front but not on the sides.

A further object of the invention resides in an undergarment of extremely simple and inexpensive construction made up of a main portion, a front panel portion and a crotch portion.

A still further object of the invention is to produce an undergarment having a substantially horizontal or straight buttocks line.

Other and further objects of the invention will be understood and appreciated by those skilled in this art, or will be apparent or pointed out hereinafter.

In the accompanying drawings wherein I have illustrated preferred embodiments of the invention:

Fig. 1 shows an undergarment responding to this invention as it would appear during use in a semi-sitting position.

Fig. 2 is a front elevational view of the undergarment as it would appear when the wearer is in a standing position.

2

Fig. 3 is a side profile view of Fig. 2.

Fig. 4 is a rear elevational view of Fig. 2.

Fig. 5 is a front elevational view of a slightly different form of the undergarment.

5 Fig. 6 is a horizontal sectional view taken along line 6—6 of Fig. 5.

Figs. 7, 8 and 9 are, respectively, plan views of the main, front panel and crotch portions of material prior to assembly to form an undergarment 10 in accordance with this invention.

The undergarment of Figs. 1—4 and that of Figs. 5 and 6 are essentially the same, differing in minor particulars only. Each such undergarment is composed of three portions, the main 15 portion 10, the front panel portion 11 and the crotch portion 12. The main portion 10 constitutes the entire rear of the undergarment (note Fig. 4) and portions of the front thereof (note Figs. 2 and 5), so that no seams are required in

20 the rear and hip portions. Main portion 10 also has a semi-circular cut-out 13 centrally of its lower edge, and somewhat beyond cut-out 13 the material ascends steeply at an angle of about 45° to meet the vertical edges 14. Thus, when the 25 piece of material of Fig. 7 is folded over parallel to its side edges 14, it constitutes the entire rear portion of the garment and parts of the side portions. It also includes two upwardly and inwardly (when folded or in the finished garment) ex-

30 tends oblique edges adapted to cooperate with similar edges 15 of panel portion 11, so as to form a pair of spaced, inverted V-shaped cut-outs in the front of the undergarment. The vertical edges 16 of portion 11 match with vertical edges 35 14 of portion 10, as will be observed from Figs. 2 and 5 in particular, and are sewed or stitched together to form vertical seams 17. The upper edges of portions 10 and 11 are finished by means 40 of a waistband 18 of any suitable or known character such as Shirred elastic.

From Fig. 8 it will be noted that the lower edge 19 of panel portion 11 is concavely cut-out and that the width of the panel portion is less at the bottom than at the top. Concave lower edge 19 45 of portion 11 interfits with convex edge 20 of crotch portion 12 and the other convex edge 21 of crotch portion 12 interfits with the cut-out 13 of main portion 10. Crotch portion 12 has tapering side edges to provide a desired contour for 50 the comfort of the wearer. The crotch portion is sewed or stitched in place, as will be understood from Figs. 2 and 5, to form the arcuate seams 22 and 23. This completes the undergarment except for desired trimming such as the 55

edging 24 or the lace 25 or other utilitarian or ornamental accessory.

An undergarment made in accordance with this invention gives exceptional freedom of leg movement, due to the inverted V-shaped cut-outs in the front of the garment, without any undesired bunching or pulling of the material. A garment constructed as described contains a minimum of material and fits smoothly at all times so that it does not form visible bunches or ridges even under the sheerest of outergarments. The buttocks line always remains straight or flat, thus being always comfortable and protective regardless of the position of the wearer in distinct contrast to prior types of undergarments.

The foregoing is intended as illustrative and not as limitative since other and further modifications thereof, may be made without departing from the spirit or principles hereof. The invention is rather that defined by the appended claims.

Having thus described my invention, what I claim as new and desire to secure by Letters Patent is:

1. An undergarment comprising a main portion constituting the entire back and sides of such undergarment and extending from the waistline downwardly, its side edges diverging downwardly from about midway of its height, a panel portion secured between the side parts of the main portion above the points of divergence, its side edges converging downwardly from said points, a crotch portion secured at one end to said panel portion and at the other end to said main portion, the side edges of the front part of said crotch portion converging downwardly and constituting a continuation of the corresponding converging side edges of the respective sides of the panel portion, said converging and diverging edges bounding an inverted V-shaped cut-out to overlie the front of each leg of a wearer with the apex of the V on the front center line of the leg.

2. An undergarment formed of three blanks, a first blank embodying a horizontal waistline edge, and two substantially vertical side edges extending down approximately half the height of the blank, downwardly converging edges extending respectively from the lower termini of said side edges to a horizontal bottom edge which has

a centrally located concave edge; a second blank embodying a horizontal waistline edge which together with the waistline edge of the first blank completely encircles the waistline, vertical side edges which are coextensive with and seamed to the respective side edges of the first blank, downwardly converging edges extending respectively from the lower termini of said side edges of the second blank, and a concave bottom edge joining the terminals of said converging edges, the converging edges of the 1st and 2nd blanks opposing each other to provide an inverted V-shaped cut-out for overlying each leg of a wearer with the apex of the cut-outs lying on the front center line of each leg; and a third blank embodying a convex upper edge coextensive with and seamed to the concave edge of said first blank, downwardly converging side edges extending from the termini of the convex upper edge to about one-third of the height of said third blank, diverging side edges extending downwardly from the lower termini of said converging side edges to a convex lower edge which joins their lower termini; said lower convex edge being coextensive with and seamed to the lower concave edge of said second blank and the diverging side edges of said third blank being in line with and constituting a continuation of the corresponding converging side edges of the respective sides of the second blank.

JULIUS SCHWARTZ.
